UNITED STATES PATENT OFFICE.

HARTLEY BLYTH PRATT, OF BARROW-IN-FURNESS, ENGLAND, ASSIGNOR TO VICKERS LIMITED, OF WESTMINSTER, ENGLAND, A BRITISH COMPANY.

SUBMARINE MINE.

Application filed June 28, 1926, Serial No. 119,045, and in Great Britain November 27, 1925.

This invention relates to submarine mines of the kind in which the flotation chamber or mine proper and the anchor sink as a unit to a predetermined depth (or to the sea bottom) where the flotation chamber is released from the anchor to enable the flotation chamber to ascend until it reaches the predetermined set depth at which it is to be anchored, whereupon a hydrostatic device 5 carried by the flotation chamber comes into operation to stop the paying out of the mooring cable, this device being of the type comprising a drum which is carried by the flotation chamber and carries an auxiliary wire connected to a contrivance situated in the anchor for stopping the paying out of the cable by the pull which is exerted on the said auxiliary wire when the rotation of the drum is stopped by a locking device which is 10 moved into the arresting position when the set depth is reached, this depth being determined by a diaphragm one side of which is open to the sea and the other is acted upon by an adjustable counter-pressure. In 15 hydrostatic devices of the drum type referred to above the said counter-pressure has heretofore been obtained by an adjustable spring arranged in a casing in which the drum rotates.

According to the present invention the adjustable counter-pressure in a hydrostatic device of the drum type referred to above is obtained by compressed air which is 20 passed into the chamber containing the diaphragm until the pressure corresponding to the required set depth is reached. The said chamber is preferably formed in the drum itself and the diaphragm may normally be locked in the inoperative position by a catch held in place by a shearing pin which, when the flotation chamber separates from the anchor, is sheared by the pull on a cable or wire connecting the said catch to the anchor. The aforesaid locking device may 25 be carried by the aforesaid drum and its movement into engagement with the fixed casing, instead of being effected as heretofore by the movement of a member connected to the diaphragm upon which the hydrostatic pressure acts in opposition to the adjustable counter-pressure, is effected by a cocked spring-actuated member which, upon the set depth being attained, is released by the movement of the diaphragm so as to 30 operate upon the said locking device.

In order that the said invention may be clearly understood and readily carried into effect, the same will now be described more fully with reference to the accompanying drawings, in which:—

Figure 1 is an axial section shewing a constructional form of hydrostatic depth setting device in accordance with this invention, and

Figure 2 is an end view of Figure 1. 65
 A is the drum which carries the auxiliary wire A¹ and is rotatably mounted in a casing B connected to the flotation chamber. The wire is kept under suitable tension during the paying out operation by a friction brake comprising a number of spring pressed pads b which are carried by the end plate of the casing B and which bear against a fibre ring a on the drum. The diaphragm C is arranged within the drum and divides the interior of the drum into two separate compartments C^x, C^{xx} of which the latter is open to the sea through the holes c^x, c^{xx}, the sea water acting upon the right hand part of the diaphragm through a hole c^{xx}. The other compartment C^x contains a light spring C¹ and is supplied with compressed air through an axial hole in a stem C² to which the diaphragm is connected. At its outer end this stem has a plug c normally closing the axial hole and a non-return valve c¹ for retaining the air pressure until the plug c has been replaced after a pumping operation, the compressed air being preferably furnished by a hand or foot pump connected to the said stem in place of the plug. The drum carries a gauge B¹ which communicates in an airtight manner with the left hand compartment of the drum and which is graduated in depths measured in metres for example. 90 The spring C¹ is intended to provide for the minimum depth setting which may be 3 metres.

The aforesaid stem C² is normally locked in its "in" position by a sliding catch or bolt D which is connected to the casing B by a shearing pin D¹. This catch has an eye to which is connected a wire or cable attached to the anchor so that when the flotation chamber separates from the anchor the said shearing pin will be severed and the catch removed from the casing so that it no longer restrains the outward movement of the stem C², it being understood that in the type of mine to which this invention re- 110

lates the separation of the flotation chamber from the anchor takes place when the unit has sunk to a predetermined depth exceeding the maximum depth at which the flotation chamber is to be anchored.

E is the aforesaid locking device for the drum A and is in the form of a spring controlled pin slidably carried by the drum. This pin, when pushed out, engages with lugs B² on the fixed casing B and thereby stops the rotation of the drum. The aforesaid spring operated member for effecting the engagement of the pin E with the lugs B² is in the form of a collar F slidably carried by a sleeve F¹ fixed to the drum and between this collar and a part connected to the said sleeve is a compressed spring F². The collar F is normally locked to the sleeve F¹ by balls f¹ which are disposed in holes passing through the said sleeve and engaged in a recess f with inclined walls formed in the collar F. The aforesaid stem C² is formed with a groove c² which is normally a short distance away from the balls f¹ but which, when the diaphragm C moves to the right upon the predetermined set depth being reached, comes opposite the balls which are thereupon forced out of engagement with the recess f by reason of the inclined walls of this recess. The collar F is thus liberated and the spring F² thereupon presses it against the pin E to move the latter forcibly into engagement with the aforesaid lugs B¹ on the casing B. It will be understood that as the catch D is moved to the unlocking position at a depth of immersion exceeding the maximum set depth required as aforesaid, the diaphragm C will at such time be held in the position shown (i. e. deflected to the left) by the sea pressure and as the latter decreases as a result of the rising of the flotation chamber due to its buoyancy, the air pressure in the compartment C* will move the diaphragm towards the right; this action continues until, when the two pressures are equal, the groove c² comes opposite the balls f¹ to release the collar F as above described.

The herein described invention is particularly but not exclusively intended for use with submarine lines constructed in accordance with the specifications of our patent applications Serial Numbers 119,044 and 119,046, filed concurrently herewith in which the stoppage of the drum C shears a shearing pin normally holding the locking pawl of the mooring cable drum in the inoperative position and also shears a shearing pin detachably connecting the hydrostatic device to the flotation chamber.

What I claim and desire to secure by Letters Patent of the United States is:—

1. For use in a submarine mine comprising a flotation chamber separable from an anchor which holds the flotation chamber by

means of a mooring cable at a predetermined depth beneath the surface of the water, a depth setting device comprising a casing, a drum rotatably mounted in said casing, a wire on said drum connected to a device adapted to stop the paying out of the mooring cable when the rotation of said drum is stopped, a locking device adapted to arrest the rotation of said drum, a chamber, means for admitting to said chamber gas under pressure corresponding to the predetermined set depth, a diaphragm acted upon by said gas on one side and by the pressure of the water on the other side, and means under the control of said diaphragm whereby, when a water pressure corresponding to said depth is reached, said locking device will be moved to its position arresting the rotation of said drum.

2. For use in a submarine mine comprising a flotation chamber separable from an anchor which holds the flotation chamber by means of a mooring cable at a predetermined depth beneath the surface of the water, a depth setting device comprising a casing, a drum rotatably mounted in said casing, a wire on said drum connected to a device adapted to stop the paying out of the mooring cable when the rotation of said drum is stopped, a locking device adapted to arrest the rotation of said drum, a chamber formed in the interior of said drum, means for admitting to said chamber gas under pressure corresponding to the predetermined set depth, a diaphragm acted upon by said gas on one side and by the pressure of the water on the other side, and means under the control of said diaphragm whereby, when a water pressure corresponding to said depth is reached, said locking device will be moved to its position arresting the rotation of said drum.

3. In a depth setting device for a submarine mine, the combination with the elements claimed in claim 1, of a catch adapted to normally lock the diaphragm in the inoperative position and a shearing pin adapted to normally hold said catch in the operative position, said pin being sheared when the paying out of the mooring cable is stopped by said depth setting device.

4. In a depth setting device for a submarine mine, the combination with the elements claimed in claim 2, of a catch adapted to normally lock the diaphragm in the inoperative position and a shearing pin adapted to normally hold said catch in the operative position, said pin being sheared when the paying out of the mooring cable is stopped by said depth setting device.

5. For use in a submarine mine comprising a flotation chamber separable from an anchor which holds the flotation chamber by means of a mooring cable at a predetermined depth beneath the surface of the water, a

depth setting device comprising a casing, a drum rotatably mounted in said casing, a wire on said drum connected to a device adapted to stop the paying out of the mooring cable, when the rotation of said drum is stopped, a locking device adapted to arrest the rotation of said drum, a diaphragm, means for enabling the pressure of the water to act on one side of said diaphragm, means 10 for causing to act on the other side a pressure corresponding to the predetermined set depth, a normally cocked spring-operated member for moving said locking device to the locking position, and a releasing device 15 for said member, said releasing device being operated by said diaphragm to release said member to move the locking device to its locking position when the predetermined set depth has been reached.

20 6. For use in a submarine mine comprising a flotation chamber separable from an anchor which holds the flotation chamber by means of a mooring cable at a predeter-

mined depth beneath the surface of the water, a depth setting device comprising a casing, a drum rotatably mounted in said casing, a wire on said drum connected to a device adapted to stop the paying out of the mooring cable when the rotation of said drum is stopped, a locking device adapted to 25 arrest the rotation of said drum, a chamber within said drum, means for admitting to said chamber gas under pressure corresponding to the predetermined set depth, a diaphragm 30 acted upon by said gas on one side and by the pressure of the water on the other side, a normally cocked spring-operated member for moving said locking device to the locking position, and a releasing device 35 for said member, said releasing device being operated by said diaphragm to release said member to move the locking device to its locking position when the predetermined set depth has been reached.

HARTLEY BLYTH PRATT.
